A. NOVICK.
BLANK LOCATING DEVICE,
APPLICATION FILED SEPT. 22, 1919.

1,407,565.

Patented Feb. 21, 1922.

Inventor:
Abraham Novick
by *Charles McStone*
his Attorney.

UNITED STATES PATENT OFFICE.

ABRAHAM NOVICK, OF NEW YORK, N. Y., ASSIGNOR TO F. L. SMITH THE MACHINE COMPANY, INCORPORATED, OF NEW YORK, N. Y., A CORPORATION OF NEW YORK.

BLANK-LOCATING DEVICE.

1,407,565.

Specification of Letters Patent. Patented Feb. 21, 1922.

Application filed September 22, 1919. Serial No. 325,449.

To all whom it may concern:

Be it known that I, ABRAHAM NOVICK, a citizen of the United States, and a resident of New York, borough of Manhattan, in the 5 county of New York and State of New York, have invented certain new and useful Improvements in Blank-Locating Devices, of which the following is a specification.

This invention relates to blank locating 10 devices, particularly adapted for use in connection with blank feeding mechanisms, such for instance as shown in my U. S. Patent No. 1,296,690, of March 11, 1919. The object of my improvements is to provide a device 15 of the class specified which is efficient to correct the natural tendency of the rear ends of the blanks to deviate laterally one way or the other from their desired path of travel under the action of the feeding mechanism while being withdrawn one by one 20 from the pile of blanks.

With this object in view my improvements comprise features illustrated in their preferred embodiment in the drawing accompanying 25 this specification, wherein the figure shows a plan view of so much of a blank locating device as will suffice to illustrate my improvements.

Referring thereto, 2, 3 represent opposite 30 side-rails connected by rear-rail 4. Front-rail 5 is preferably adjustably fixed to said side-rails, so as to accommodate blanks of different sizes. Slidably mounted on said rail 5 are opposite brackets 6, 7 carrying 35 guide-posts 8, 9, respectively. Said brackets may be secured in adjusted positions by screws 10. Parallel with front-rail 5 and located near rear-rail 4 is transverse slide 11 on which are adjustably fixed brackets 12, 40 13 carrying guide-posts 14, 15, respectively, all similar to the guide posts and their brackets on rail 5. Said guide posts are efficient for locating one or more blanks 45 supported on table 16 parallel with rail 5 and slide 11. Said table may be supported and raised or lowered from time to time by some known means, not shown. The character of blank illustrated has four 50 notched corners, which are engaged by said posts, and which blank is adapted to be folded into an envelope.

Slide 11 is conveniently mounted under straps 17, 18 on rails 2, 3, respectively, for transverse movement in the direction of its 55 length in parallelism with the blank and in

substantial parallelism with rail 5. For thus moving slide 11 shaft 19 rotatably mounted in ears 20, 20 outstanding from rail 3 is provided. Said shaft has fixed to its rear end gear 21, in engagement with rack 22, 60 fixed to the overhanging portion of slide 11, and to its front end hand-wheel 23. Thus by turning said hand-wheel to the right, slide 11 and posts 14, 15 will be shifted to the left, carrying the tail-ends 25^a of blanks 65 25 therewith; by turning said hand-wheel to the left the tails of the blanks will be shifted to the right. There is thereby provided a mobile and effective adjustment for the blanks, whereby any tendency to advance 70 in skewed position is corrected. Also said adjustment, one way or the other, may be made while the machine, to which the device is applied, is running, and without in any way deranging its operation. 75

I claim:

1. In a blank locating device the combination of means for locating one end of the blank, means for locating the other end of the blank relatively to said first end, and 80 means for moving laterally said last mentioned locating means.

2. In a blank locating device the combination of two fixed posts for locating one end of the blank, two other posts fixed relatively 85 to each other for locating the other end of the blank, and hand operated means for moving transversely said other posts in unison for adjusting the location of said other end of the blank. 90

3. In a blank locating device the combination of means for locating one end of the blank, means for locating the other end of the blank, a slide mounted for movement transversely in the plane of the blank, said 95 means for locating the other end of the blank being carried by said slide, and means for moving said slide.

4. In a device for locating a blank having four notched corners, two fixed posts for engagement with two of the notched corners, respectively, two other posts for engagement with the other two notched corners, respectively, of the blank, a slide mounted for movement transversely in the plane of the 100 blank, said two other posts being carried by said slide, and hand operated means for moving said slide. 105

5. In a device for locating a blank having four symmetrically disposed notched cor- 110

- ners, two adjustably fixed posts for engagement with two of the notched corners, respectively, a slide mounted for movement in the plane of the blank and in a line parallel 5 with a line through the axes of said two posts, two other posts adjustably mounted on said slide for engagement with the other two notched corners, respectively, of the blank, and means for moving said slide.
- 10 6. In a blank locating device the combination of means for locating the blank, and means for adjusting said locating means for correcting angular deviation of the blank from its desired path of travel.
- 15 7. In a blank locating device the combination of means for locating one end of the

blank, means for locating the other end of the blank, and means for adjusting said last mentioned means for correcting lateral deviation of the blank from its desired path of 20 travel.

8. In a blank locating device the combination of means for locating one end of the blank, means for locating the other end of the blank, means for adjusting said last 25 mentioned means for correcting lateral deviation of the blank from its desired path of travel, and hand operated means for moving said adjusting means.

In witness whereof, I hereby affix my sig- 30
nature this 19th day of September, 1919.

ABRAHAM NOVICK.
